UNITED STATES PATENT OFFICE.

FREDRICK W. FISCHER, OF MILWAUKEE, WISCONSIN.

MACHINE FOR TREATING WICKS.

Application filed March 25, 1921. Serial No. 455,592.

To all whom it may concern:

Be it known that I, FREDRICK W. FISCHER, a citizen of the United States, residing at Milwaukee, in the county of Milwaukee and 5 State of Wisconsin, have invented new and useful Improvements in Machines for Treating Wicks, of which the following is a specification.

This invention relates to the art of weaving wicks and an object of the invention is to provide a process which will increase the longevity of wicks, such as used in lamps, oil stoves, etc., by impregnating the wicks with a non-combustible material, which, 10 while retarding the burning of the wicks, does not impair the capillary action thereof.

The wicks commonly used in oil stoves, lamps, and the like are woven from relatively soft cotton thread and consequently are comparatively soft permitting easy distortion of the shape of the wick which results in an uneven flame, as well as uneven burning and trimming of the wick and to 25 overcome this the wicks are also treated with a stiffening agent, such as a solution of starch or the like.

Another object of the invention is to provide a machine for feeding wicks and preparing them for market after they have been woven, which machine will materially decrease the labor contingent with performing the various steps in the above mentioned process and also decrease the labor necessary 35 in completing the wicks.

Another object of the invention is to provide a machine as specified which includes a movable table carrying a plurality of collapsible wick carrying arbors with which 40 table are associated means for treating the wicks with a stiffening agent, and means for drying the stiffening agent. The stiffening agents which are adaptable for stiffening the wicks are necessarily of such consistency 45 that they will not be readily absorbed by the wick structure, especially in cases where they are sprayed upon the wicks and to assist in the thorough impregnating of the wicks with the stiffening agent a pressure 50 roller is provided which forces the stiffening agent into the fabric of the wick and also serves to rotate the wick during the spraying of the stiffening agent thereon to cause even distribution of the stiffening agent over the wicks.

In the present practice or manufacture of substantially cylindrical wicks, after the wick is formed the upper edge is burned to make it even, however, owing to the softness of the wick structures they, quite frequently, become distorted especially at their upper edges and consequently burning does not always result in the even straight edge on the wicks, and it is an object of this invention to provide means, 60 associated with the improved machine, for trimming the wicks, preferably, by means of a rapidly rotating knife which will cut the upper edges of the wicks evenly and with square even burning edges. 70

A still further object of this invention is to provide means for moving the table of the machine, which means is operated intermittently, permitting the table to remain stationary at predetermined intervals during 75 which intervals the wicks carried by the table are treated or sprayed with the stiffening agent and trimmed and also during certain of which intervals the collapsible wick carrying arbors are released to permit easy 80 removal of the wicks therefrom.

Other objects of the invention will appear in the following detailed description and in the accompanying drawings wherein:

Fig. 1 is a top plan of the improved wick 85 treating machine.

Fig. 2 is a vertical section through the improved wick treating machine.

Fig. 3 is a horizontal section through the wick treating machine taken below the table 90 thereof.

Fig. 4 is an enlarged detail, partly in section of the improved wick treating machine.

Fig. 5 is an enlarged detail, partly in 95 section of the wick treating machine illustrating the mechanism for drying the wicks after being impregnated with the stiffening agent.

Fig. 6 is a detail plan of an expandible 100 wick carrying arbor used in the machine.

Fig. 7 is a diagrammatic view of a modified form of the invention.

Referring more particularly to the drawing the improved wick treating machine, 105 which is particularly designed for treating wicks of the type used in kerosene stoves and lamps employing round or cylindrical wicks such as clearly shown in Fig. 8 of the drawing, comprises a supporting struc- 110

ture 1 which includes a bed-plate 2. The supporting structure 1 is of sufficient strength to firmly support the movable parts of the machine and it carries a barrel bearing 3 which rotatably supports the table carrying spindle 4. The table 5 is mounted upon the spindle 4 and connected thereto, for rotation with the spindle, in any suitable manner. The table 5 has a plurality of pins 6 connected thereto and spaced in a circle concentric of the axis of the table. The heads 7 of which pins project beneath the under surface of the table and are adapted to be engaged, one at a time, by a pawl 8 carried by a cross head 9. The pawl 8 is pivotally connected as shown at 10 to the cross head 9 and is yieldably supported in a head engaging position by a spring 11 which supports the pawl in its upward position with its upper surface inclining downwardly towards the pivot of the pawl, as clearly shown in Fig. 2 of the drawing. The cross head 9 has a transverse pin 12 carried thereby which is engaged by the forked end 13 of an arm 14. The arm 14 is pivotally mounted upon a stub shaft 15 and has a second arm 16 connected thereto. The arm 16 is connected, by means of an eccentric 17 to a power shaft 18 of the machine so that when the shaft 18 is rotated the eccentric 17 will move the arm 16 in a substantially longitudinal manner, locking the arm 14 for moving the cross head 9 longitudinally over its guide bar 19. The guide bar 19 is arranged tangentially of a circle intersecting the axes of the pins 6, as clearly shown in Fig. 1 of the drawings so that the longitudinal movement of the cross head 9 thereon will, through the engagement of the pawl 8 with one of the pins 7, move the table 5 forward one step. When the cross head 9 recedes or returns to its normal position, under movement of the levers 14 and 16 by the eccentric 17, the inclined upper surface of the pawl 8 engaging the head 7 of the pin just engaged by the end of the pawl will press or tension the spring 11 permitting the head to return to its normal position without moving the table 5.

The table top is provided with an annular upstanding portion 20 which is in turn provided with an under cut annular groove 21 providing annular shoulders 22. Wick carrying arbors 23 are provided which are positioned at spaced intervals about the table top 5 and concentric of the axes of the table top as well as at predetermined positions relative to the pins 6. The arbors 23 comprise sections 24 and 25 the outer surfaces of which are curved to snugly fit within a wick as clearly shown in Fig. 9 of the drawing and they are supported to securely grip a wick and maintain it in engagement with the arbor by a spreader

structure 26. The spreader structure 26 comprises spreading blocks 27 and 28' which engage in the inner surfaces of the sections 24 and 25 and which are forced apart by a spreading wedge 28. The wedge 28 has shank 29 formed thereon which extends through an opening 30 in the table top, and is provided with ball bearing thrust bearings 31 and 32 to relieve friction in the rotation of the arbor. A nut 33 is mounted upon the lower end of the shank 29 and serves to confine a washer 34 thereon against which the lower end of an expansion spiral spring 35 engages while the upper end of the spring engages against the bearing 32 thus urging the spreading wedge 28 downwardly between the spreading blocks 27 and 28 to urge the arbor sections 24 and 25 apart.

The arbor sections 24 and 25 are provided with arcuate grooves 36 which engage the overhanging flanges 37 on the table top, the projections 20 forming a secure connection between the arbor sections 24 and 25 and the table top. In practice when wicks are to be placed upon the arbors and carried by the table, the wedge, of the individual arbors to receive the wicks at a certain time, is forced upwardly to relieve the arbor sections 24 and 25 to permit them to collapse or move inwardly and this operation is provided at a predetermined time during operation of the machine so that as each arbor reaches a predetermined position, the spreader structure 26 is released by a cam 38 which engages a roller 39 on a cross head 40. The cross head 40 is slidably mounted upon spaced rods 41, one of which is positioned upon each side of the shank 29 and which rods are carried by and movable with the table 5. When the point or apex 42 of the cam 38 is in engagement with the roller 39 the cross head 40 will be forced upwardly to its maximum position at which time the spreading wedge 28 will also be forced upwardly to its maximum position permitting the arbor sections 24 and 25 to move inwardly for removing the treated wick therefrom and replacing it with a wick to be treated, after which continued rotation of the cam 38 releases the cross head 40 allowing it to move downwardly for spreading the arbor sections 24 and 25 by the action of the spring 35. The cam 38 is carried by a shaft 43, which is in turn connected, by suitable mitre or bevel gears 44, to a shaft 45. The shaft 45 is, in turn, connected by bevel or mitre gears 46, to a vertical shaft 47 and this shaft 47 is connected in any suitable manner, such as by gears 48 to the power shaft 49 of the machine. The particular arrangement of the shafts 43, 45, 47 and 49 does not enter into the present invention, they being shown merely as a preferred form of invention for the purpose of

illustrating a relatively compact, complete machine and if found necessary the cam 38 may be operated by any approved form of power transmitting mechanism without departing from the spirit of this invention. After the wicks have been placed upon the arbors they are moved with a step by step movement of the table until finally the wick on the arbor is engaged by a roller 50 during one of the arrested intervals in the movement of the table 5. The roller 50 is driven from the power shaft 49 by suitable bevel gears 51 which are mounted upon a roller carrying shaft 52 and the roller frictionally engages the wick upon the arbor adjacent to the roller above the metal brace or shell 53 of the wick. As shown in Fig. 11 of the drawing the improved wick 54 is cylindrical in shape and is braced by the usual form of metal brace or shell 53 which is perforated as shown at 55 to permit capillary action of the wick and is bent over the lower edge of the wick as shown at 56 to securely connect the sheel of the wick structure.

As previously stated the roller 50 engages the wick 54 above the metal shell 53 and the rotation of the roller 50 will rotate the arbor which is carrying the wick engaged by the roller and consequently rotate the wick.

During the rotation of the wick by the roller 50 a stiffening agent is applied to the outer surface of the wick above the shell 53 through a nozzle 60. The stiffening agent may be starch, or an analogous product, and is contained in a suitable container 61 and passes into the nozzle 60 through a branch pipe 62 on the nozzle which has an injector-like outlet into the nozzle so that air, passing through the nozzle 60 at a high velocity from the air supply pipe 63, will draw the stiffening agent into the nozzle and spray it therefrom upon the wick 54. As clearly shown in Fig. 1 of the drawing the nozzle 60 is arranged to spray the wick directly in front of the roller 50 so that the roller engaging and pressing against the wick will press or force the stiffening agent into the body of the wick 54 assisting in the efficient impregnating of the portion of the wick above the portion of the shell 53 with the stiffening agent.

The passage of air through the nozzle 60 from the supply pipe 63 is controlled by a valve 64 which is, in turn, automatically opened and closed, at predetermined intervals, by a cam 65 operating through a pivoted lever 66, link 67 and an arm 68, which is connected directly to the valve 64. The lever 66 is pivotally connected at one end as shown at 69 and is provided with a slot 70, intermediate its ends, which slot receives the angled end 71 of a rod 72. The rod 72 is connected by a turn buckle 73 with a second rod 74 which carries a cam engag-

ing roller 75, the perimeter of which is engaged by the cam 65 for operating the lever 66. By adjusting the turn buckle 73 the operative length of the rods 72 and 74, or in other words, the distance between the roller 75 and angled end 71, may be regulated, which, in turn, regulates the amplitude of movement of the lever 66 also regulating the amplitude of movement of the arm 68 and controlling the quantity of air admitted to the nozzle 60 upon each operation of the valve 64.

If it is so desired, the stiffening agent in the container 61 may have a non-combustible solution mixed therewith such as sulphate of ammonia, or tungstate of soda, so as to impregnate the wick with both the stiffening agent and non-combustible solution to retard the burning of the wick for increasing its longevity.

Owing to the liquid nature of the stiffening agent the wick is damp after it leaves the roller 50, it being moved therefrom by the next step in the operation of the movement of the table 5 and to dry the wick suitable drying means are provided.

In the preferred form of the invention the drying means is in the form of an arcuate radiator 77 which includes, preferably, an outer housing 78 having a suitable type of heating agent 79 therein. The drawings illustrate a heating coil such as used in steam heaters, but it is to be understood that an electric heating coil, gas burner or any approved type of heating means may be employed, without departing from the spirit of this invention.

As clearly shown in Fig. 5 of the drawing the shell 78 of the radiator 77 engages the shell 53 of the wick 54 and as the table 55 is moved, the engagement of the shell 78 with the shell 53 will rotate the wick 54 causing the proper treating of the entire outer surface of the wick.

After the wick has been dried and it leaves the end of the radiator structure 77 it is engaged by a roller 80 carried by a suitable shaft 81. The shaft 81 is rotated by the shaft 45 in any suitable manner such as by bevel gears 82 and at a high rate of speed. The roller 80 frictionally engaging the dried wick will rotate the wick and a trimming knife 83 is carried by the shaft 81 engaging against the upper surface or end of the roller 80. The cutting edge of the knife 83 projects beyond the perimeter of the roller 80 a distance equal to the thickness of the wick 53 so that as the roller 80 is rapidly rotated and the wick 53 rotated by the roller 80, the knife 83 will trim the top of the wick eliminating the need of burning the wick to provide an even upper edge thereto. Owing to the fact that the wick is held on the arbor structure during its trimming and consequently pressed against distortion, the top

of the wick will be evenly and squarely trimmed providing an even burning edge to all wicks engaged by the knife 83.

It is the practice of manufacturers to print their trade-mark or name upon wicks of the nature heretofore referred to and this is usually done by hand after the wick has been completed which necessitates extra labor and time and the present wick treating machine may be constructed to embody a printing roller 84 as shown in Fig. 1 of the drawing. The roller 84 may have any suitable stamp upon its perimeter, depending what the manufacturer desires to print on the wicks and this stamp is made in the usual manner of making rubber stamps. The printing roller 84 may be rotated from the shaft 81 by a gear train embodying gears 85, 86, 87 and this roller may be inked in any well known approved manner. After the wick leaves the printer roller 84 it moves to the delivery and receiving position of the machine relative to the spreading wedge 28 and is operated by the cam 42 to permit the removal of the completed wick from the arbor and the placing of a wick to be treated thereon, which latter wick passes about with the machine in its step by step movement and is treated as above stated.

In the foregoing description the wicks are impregnated with a stiffening agent by spraying, however, it may be necessary or desirable to impregnate the entire wick with the stiffening agent and to do this the wicks may be dipped into a stiffening solution before they are placed upon the table carried arbors. The process or act of treating the dipped wicks will necessitate a different structure than the drying structure heretofore described as the wicks will be wet both inside and outside. The drying of dipped wicks may be done in a number of approved manners, one of which is illustrated in the diagrammatic view illustrated in Fig. 7 of the drawings where a heating agent, such as steam, is passed through a supply pipe 90 to a centrally disposed distributor 91 from which the heating agent passes through a suitable pipe 92 to an arbor 93.

It is, of course, to be understood that the invention may be constructed in various other manners and the parts associated in different relations and, therefore, I do not desire to be limited in any manner except as set forth in the claims hereunto appended.

Having thus described my invention what I claim is:

1. In a wick treating machine, a movable table, wick supporting arbors carried thereby, means for spraying wicks with stiffening material while on said arbors, a pressure roller for forcing stiffening material into the wicks, and means for rotating said pressure roller.

65 2. In a wick treating machine, the combi-

nation of a movable table, wick-supporting arbors carried thereby, means for spraying wicks while on said arbors, and a rotary knife for trimming wicks on said arbors.

3. In a wick treating machine, a movable table, wick supporting arbors carried thereby, means for spraying wicks with stiffening material while on said arbors, a pressure roller for forcing stiffening material into the wicks, means for rotating said pressure roller, and trimming means for trimming wicks.

4. In a wick treating machine, a movable table, wick supporting arbors carried thereby, means for spraying wicks with stiffening material while on said arbors, a pressure roller for forcing stiffening material into the wicks, means for rotating said pressure roller, and a rotary knife for trimming wicks on said arbors.

5. The combination with a movable wick-carrying table of means for moving said table, and means for spraying a stiffening material upon wicks carried by said table, and pressure means for forcing the stiffening material into the wicks.

6. In a wick treating machine, a movable table, wick carrying arbors thereon, means for moving said table, means for applying a stiffening material to wicks on said arbors, means operated with said table moving means for operating said stiffening material applying means, a pressure roller for forcing the stiffening material into wicks on said arbors, and means for rotating said roller.

7. In a wick treating machine, a movable table, wick carrying arbors thereon, means for moving said table, means for applying a stiffening material to wicks on said arbors, means operated with said table moving means for operating said stiffening material applying means, a pressure roller for forcing the stiffening material into wicks on said arbors, means for rotating said roller, means for drying said stiffening material, and a rotary knife for trimming wicks on said arbors.

8. In a wick treating machine, the combination of a movable table, wick-carrying arbors thereon, means for moving said table, means for applying stiffening agent to wicks on said arbors, means operated with said table-moving means for operating said stiffening material applying means, means for drying said stiffening material, a rotary knife for trimming the wicks and means for rotating said knife.

9. In a wick treating machine, the combination with a movable wick-carrying table, means for moving said table, means for spraying wicks on said table with a liquid solution, and pressure means for forcing the solution into the wicks.

10. In a wick treating machine, a wick

- carrying table, means for spraying wicks on said table with a liquid material, pressure means for forcing the solution into the wicks, heating means for drying the sprayed wicks, and a rotary knife for trimming the dried wicks.
11. In a wick treating machine, the combination with a wick-carrying table, of means for spraying wicks on said table with a liquid solution, and pressure means for forcing the solution into the wicks.
12. In a wick treating machine, the combination with a wick-carrying table, of means for spraying wicks on said table with a liquid solution, pressure means for forcing the solution into the wicks, and heating means for drying the sprayed wicks.
13. In a wick treating machine, the combination of a movable table, wick-carrying arbors thereon, means for moving said table, means for applying a stiffening agent to wicks on said arbors, means for operating said stiffening material applying means, pressure means for forcing said stiffening agent into the wicks, and means for drying said stiffening agent.
14. In a wick treating machine, the combination of a movable table, wick-carrying arbors thereon, means for moving said table, means for applying a stiffening agent to a portion of wicks on said arbors, means for operating said stiffening material applying means, pressure means for forcing said stiffening agent into the wicks, and means for drying said stiffening agent.
15. In a wick treating machine, the combination of a movable table, wick-carrying arbors thereon, means for moving said table, means for applying a stiffening agent to wicks on said arbors, means operated with said table-moving means for operating said stiffening agent applying means, means for drying said stiffening agent, and means for trimming the wicks after drying.
16. In a wick treating machine the combination of a movable table, wick-carrying arbors thereon, means for moving said table, means for applying a stiffening agent to wicks on said arbors, means operated with said table-moving means for operating said stiffening agent applying means, means for drying said stiffening agent, a rotary knife for trimming wicks after drying, and means for rotating said knife.
17. In a wick treating machine, the combination of a movable table, wick-carrying arbors thereon, means for moving said table, means for applying a stiffening agent to wicks on said arbors, means operated with said table-moving means for operating said stiffening agent applying means, a radiator for drying said stiffening agent, and means on said radiator structure for rotating wicks when in proximity to the radiator and during movement of said table.
18. In a wick treating machine, the combination of a movable table, wick-carrying arbors thereon, means for moving said table, means for applying, at predetermined times, a stiffening material to wicks on said arbors, means operated with said table-moving means for operating said stiffening material applying means, means for drying said stiffening material, means for trimming the wicks after drying, and a printing roller operated from said trimming means.
19. In a wick treating machine, a movable table, means for intermittently moving said table whereby wicks carried thereby will be alternately moved in step-by-step movement and remain stationary with the table at predetermined intervals means for rotating the wicks during one of the arrested intervals of said table, means for spraying a stiffening agent upon the outer surface of the wicks during said rotation, and a radiator for drying the stiffening agent upon said wicks, said table adapted to move while the wicks are in proximity to said radiator, and means on said radiator for rotating wicks during movement of the wicks in proximity to the radiator.
20. In a wick treating machine, a movable table, means for intermittently moving said table whereby wicks carried thereby will be alternately moved in step-by-step movement and remain stationary with the table at predetermined intervals, means for rotating the wicks during one of the arrested intervals of said table, means for spraying a stiffening agent upon the outer surface of a portion of the wicks during said rotation, means for drying a stiffening agent upon said wicks, a knife for trimming said wicks after drying, and means for rotating the wicks relative to the table while being trimmed.
21. In a wick treating machine, a movable table, means for intermittently moving said table whereby wicks carried thereby will be alternately moved in step-by-step movement and remain stationary with the table at predetermined intervals, means for rotating the wicks during one of the arrested intervals of said table, means for spraying a stiffening agent upon the outer surface of a portion of the wicks during said rotation, means for drying the stiffening agent upon said wicks, a knife for trimming said wicks after drying, means for rotating the wicks relative to the table while being trimmed, and means for automatically releasing the wicks from said table after trimming.
22. In a wick treating machine, the combination of a movable table, means for moving said table, wick-carrying arbors carried by said table, a sprayer for spraying a stiffening agent upon wicks carried by said arbors, automatic means for intermittently causing spraying action of said sprayer, a

roller for rotating said wicks while being sprayed, said roller being positioned relative to the sprayer for forcing the stiffening agent into the fabric of the wick after spraying.

23. In a wick treating machine, the combination of a movable table, means for moving said table, wick-carrying arbors carried by said table, a sprayer for spraying a stiffening agent upon wicks carried by said arbors, automatic means for intermittently causing spraying action of said sprayer, a roller for rotating said wicks while being sprayed, said roller being positioned relative to the sprayer for forcing the stiffening agent into the fabric of the wick after spraying, a radiator for drying the wicks after spraying, and means on said radiator for rotating wicks during passage along the radiator by movement of said table.

24. In a wick treating machine, the combination of a movable table, means for moving said table, wick-carrying arbors carried by said table, a sprayer for spraying a stiffening agent upon wicks carried by said arbors, a radiator for drying the wicks after spraying, and means on said radiator for rotating wicks during passage along the radiator by movement of said table.

25. In a wick treating machine, the combination of a movable table, means for moving said table, wick-carrying arbors carried by said table, a sprayer for spraying a stiffening agent upon wicks carried by said arbors, automatic means for intermittently causing spraying action of said sprayer, a radiator for drying the wicks after spraying, and means on said radiator for rotating wicks during passage along the radiator by movement of said table.

26. In a wick treating machine, the combination of a movable table, means for moving said table, wick-carrying arbors carried by said table, a sprayer for spraying a stiffening agent upon a portion of wicks carried by said arbors, automatic means for intermittently causing spraying action of said sprayer, a roller means for rotating said wicks while being sprayed, said roller being positioned relative to the sprayer for forcing the stiffening agent into the fabric of the wick after spraying, a radiator for drying the wicks after spraying, means on said radiator for rotating wicks during passage along the radiator by movement of said table, means for trimming the wicks after drying, and automatically operated means for releasing wicks from said arbors after trimming.

27. In a wick treating machine the combination of a movable table, means for moving said table, wick-carrying arbors carried by said table, a sprayer for spraying a stiffening agent upon a portion of the wicks carried by said arbors, means for rotating said

wicks while being sprayed, a radiator for drying the wicks after spraying, means on said radiator for rotating wicks during passage along the radiator by movement of said table means for trimming the wicks after drying, and automatically operated means for releasing wicks from said arbors after trimming.

28. In a wick treating machine, the combination of a movable table, means for moving said table, wick-carrying arbors carried by said table, a sprayer for spraying a stiffening agent upon a portion of wicks carried by said arbors, a radiator for drying wicks after spraying, means on said radiator for rotating said wicks during passage along the radiator by movement of said table, means for trimming the wicks after drying, and automatically operated means for releasing the wicks from said arbors.

29. In a wick treating machine the combination of a movable table, means for moving said table, wick-carrying arbors carried by said table, a sprayer for spraying a stiffening agent upon wicks carried by said arbors, automatic means for intermittently causing spraying action of said sprayer, a roller for rotating said wicks while being sprayed, said roller being positioned relative to the sprayer for forcing the stiffening agent into the fabric of the wick after spraying, a radiator for drying the wicks after spraying, means on said radiator for rotating wicks during passage along the radiator by movement of said table, and automatically operated means for releasing said arbors to permit the removal of wicks therefrom.

30. In a wick treating machine, a movable table, means for intermittently moving said table whereby wicks carried thereby will be alternately moved in step by step movement and remain stationary with the table at predetermined intervals, means for rotating the wicks during one of the arrested intervals of said table, means for forcing a stiffening agent upon wicks carried by the table during its rotation, means for drying the stiffening agent upon the wicks, said wicks carried upon the table by collapsible arbors, expanders for expanding said arbors, and means normally urging said expanders into arbor expanding positions.

31. In a wick treating machine, a movable table, means for moving the table, collapsible wick carrying arbors on said table, expanders for expanding said arbors, means normally urging said expanders into arbor expanding position for retaining wicks thereon, means for intermittently moving said table whereby wicks carried thereby will be alternately moved in step by step movement and remain stationary with the table at predetermined intervals, means for rotating wicks relative to the table during

one of the arrested intervals of the table, means for applying a stiffening agent to the wicks during said rotation, means for drying the stiffening agent after applying to the wicks, cross heads movably supported by said table and engaging said expanders, and means for moving said cross heads at predetermined times to move said expanders out of arbor expanding position to permit removal of dried wicks from said arbors.

32. In a wick treating machine, a movable table, means for moving the table, collapsible wick carrying arbors on said table, expanders for expanding said arbors, means normally urging said expanders into arbor expanding position for retaining wicks thereon, means for intermittently moving said table whereby wicks carried thereby will be alternately moved in step by step movement and remain stationary with the table at predetermined intervals, means for rotating wicks relative to the table during one of the arrested intervals of the table, means for applying a stiffening agent to the wicks during said rotation, means for drying the stiffening agent after applying to the wicks, cross heads movably supported by said table and engaging said expanders, means for moving said cross heads at predetermined times to move said expanders out

of arbor expanding positions to permit removal of dried wicks from said arbors, a knife for trimming said wicks after drying, and means for rotating wicks relative to the table while being trimmed.

35

33. In a wick treating machine, a table, wick carrying arbors thereon, a roller for engaging wicks on said arbors at predetermined times to rotate the wicks, means for rotating said roller, spraying means for spraying wicks during rotation by said roller.

40

34. In a wick treating machine, a movable carrying table, means for moving the table, means for applying a stiffening agent to a portion of wicks carried by said table, means for operating said stiffening agent applying means, pressure means for forcing said stiffening agent into the wicks, and means for drying said stiffening agent.

45

35. In a wick treating machine, a movable wick carrying table, means for moving the table, means for applying a stiffening agent to wicks carried by said table, and means operated with said table moving means for operating said stiffening agent applying means, and means for trimming the wicks after spraying.

55

In testimony whereof I affix my signature.
FREDRICK W. FISCHER.
